UNITED STATES PATENT OFFICE.

CHARLES C. WORTHINGTON, OF DUNNFIELD, NEW JERSEY.

DESIGN FOR A DUPLEX PUMP-FRAME.

SPECIFICATION forming part of Design No. 30,497, dated April 4, 1899.

Application filed March 10, 1899. Serial No. 708,610. Term of patent 14 years.

To all whom it may concern:

- Be it known that I, CHARLES C. WORTHINGTON, a citizen of the United States, residing at Dunnfield, county of Warren, and State of New Jersey, have invented and produced a certain new and original Design for a Duplex Pump-Frame, fully described and represented in the following specification and the accompanying drawings, forming a part of the same.
- 10 This invention relates to a new and original design for a duplex pump-frame; and the invention consists in a peculiar shape or configuration of the same, substantially as shown in the accompanying drawings, in which—
- 15 Figure 1 is a side view of a duplex pump-frame embodying the invention. Fig. 2 is a plan view of the same; and Fig. 3 is a perspective view of the same, looking from the suction and delivery end.
- 20 The leading feature of the design is the peculiar shape and configuration of the pump-frame, as shown, with the water-cylinders A arranged below and curving outward from the

single-pulsation and valve chamber B and the force-chamber B' upon the chamber B and 25 with the suction connection C entering from the end of the pump below and between the cylinder-heads and the force connection D on the chamber B at the end of the pump above and between the cylinder-heads. The cylinders A are shown as formed with flanges E at opposite ends, into which the pulsation and valve chamber B develops, and with the supports F, by which the pump-frame is mounted on the base G. 30

35 What I claim is—

The design for a duplex pump-frame, substantially as shown and described.

In testimony whereof I have hereunto set my hand in the presence of two subscribing 40 witnesses.

CHARLES C. WORTHINGTON.
